UNITED STATES PATENT OFFICE.

WILLIAM A. TURNER, OF PROVIDENCE, RHODE ISLAND, ASSIGNOR TO
JOSEPH DAVOL, OF SAME PLACE.

ATOMIZER.

SPECIFICATION forming part of Letters Patent No. 276,940, dated May 1, 1883.

Application filed February 6, 1883. (No model.)

To all whom it may concern:

Be it known that I, WILLIAM A. TURNER, of the city and county of Providence, in the State of Rhode Island, have invented certain new and useful Improvements in Bulb-Atomizers; and I do hereby declare that the following specification, taken in connection with the drawings furnished and forming a part of the same, is a clear, true, and complete description of my invention.

Bulb-atomizers as heretofore constructed may be properly divided into two general classes—viz., those which are intermittent and those which are continuous in their operation. The continuous atomizers necessarily involve the use of two valves, and also a section of flexible tube, or its equivalent, serving as an expansible air-chamber between the bulb and jet-pipe. Intermittent atomizers sometimes contain one valve, sometimes two, and in one variety thereof no valves are used, because in them the induction of air to the bulb is by way of the air-jet pipe, which alternately serves as an eduction and induction passage for air, the atomizing being performed at each eduction. My improvements pertain to such bulb-atomizers as contain one or two valves, whether organized to operate as intermittent or continuous atomizers.

So far as my knowledge extends, the bulbs in atomizers containing two valves have heretofore been provided with a metallic coupling-neck with a valve therein, and at the opposite end of the bulb a valve-neck containing a valve which freely admits but prevents the eduction of air. These valve-necks have each heretofore been constructed in two parts, united by screw-joints.

The objects of my invention as applied to a two-valve atomizer are to obviate the necessity for one of said necks, thereby economizing in labor and material; to lessen the liability of leakage to the extent of one-half of that incident to the use of two necks, and to increase the durability of the bulbs, it being well known that they are more liable to crack adjacent to the necks inserted therein than at any other parts thereof.

It is not new to provide for but one bulb-neck in such atomizers as have no valve, nor in some of those that have one valve; but

prior atomizers having one valve, one neck or standard, and a bulb connected at one end thereof have had at the other end of said standard a cork plug for immediately connecting said neck with the bottle which contains the liquid, and the valve in this class of atomizers is located at one side of said standard, opposite the discharge-orifice or air-jet pipe, which projects laterally from said standard, the latter containing, also, a valve-chamber, air-passages radiating therefrom, and a passage and a communicating tube for the liquid. As compared with the last-described prior atomizers having one valve, I seek to avoid expensive complexity in the construction of the standard, and as compared with the prior atomizers having no valve, I seek to prevent the draft of objectionable and sometimes destructive volatile matters into the bulb, as is liable to occur when the air is drawn inward and forced outward through the same air-jet aperture at which the atomizing is performed.

Another object of my invention is to economize in the cost of producing the valve-necks, which in their best form, according to my invention, are constructed in one part or piece, instead of in two pieces, as prior forms of neck have heretofore been made, and as one of my metallic necks in one piece takes the place of two necks, each in two parts, as heretofore, the economy accruing from my invention in its best form will be obvious, although certain other of the advantages named will accrue if my necks are made in two parts.

To more particularly describe my invention, I will refer to the accompanying drawings, in which—

Figure 1 is a side view of a continuous atomizer embodying my improvements in their best form. Fig. 2 is a central section of the improved neck. Fig. 3 shows two end views of the same. Fig. 4 is a side view of an intermittent atomizer embodying my improvements, the valve-neck being shown in section. Fig. 5 is a sectional view of one of my improved valve-necks constructed in two parts.

The flexible rubber bulbs A may be truly spherical, or, as is preferable, spheroidal, as shown, and it is to be understood that, although I am not the first to employ atomizer-bulbs having a single opening, I am the first

to so organize a continuous atomizer embodying valves that a bulb having a single opening or aperture can be used therewith. I am also the first to so organize an intermittent atomizer that a bulb having a single opening need not be applied directly to a standard, which at its opposite end enters the bottle which contains the liquid; but a bulb with but one opening, as hereinafter described, is applied by me to a neck which contains an air-induction passage and valve, and is interposed between the bulb and an air pipe or tube, which is connected at its opposite end to the standard, which in part occupies a bottle, and which in turn contains the pipe through which the liquid is delivered from the bottle for atomizing.

The atomizer illustrated in Figs. 1 to 3, inclusive, is of the continuous variety, because of the presence of the short length of flexible rubber tubing *a*, or equivalent expansible air-chamber, interposed between the bulb and the atomizer-standard *B*, it being understood that the latter and said tubing may be indefinitely varied without departure from my invention.

The valve-neck *C*, Figs. 1 to 3, inclusive, is novel, in that it contains two independent passages, *b* and *c*. The passage *b* is the air-induction passage communicating with the interior of the bulb from outside of the neck, as clearly indicated, and the passage *c* is the air-eduction passage communicating between the interior of the bulb and the interior of the flexible and expansible air-tube *a*. For preventing exit of air by way of induction-passage *b*, it is provided at its inner end with the valve *b'* within the bulb, and to prevent induction of air from the atomizer-standard and tube *a* the eduction-passage *c* is provided at its outer end with the valve *c'*. As hereshown, these valves are small flat pieces of flexible rubber, secured at one side to the neck, either by a rivet, or, as is preferable, by an overhanging portion of the neck itself, which, being composed of soft metal, can be forced down upon said valves, thus firmly securing them in place. Other forms of valves may be employed without departure from my invention; but those used by me are but little liable to derangement as compared with the disk-valves usually employed.

I am the first, so far as I know, to combine with one bulb-neck in an atomizer two valves, respectively for controlling the induction and eduction of air, regardless of the particular arrangement of the air-passages therein.

As thus far described, it will be obvious that the compression of the bulb will cause its charge of air to be forced through the passage *c*, which will be closed by its valve when the bulb is released from pressure, and that the bulb will thereupon become filled with air by way of the induction-passage *b*, its valve freely lifting meanwhile. As thus constructed it will be seen that, as compared with prior atomizers operating continuously, I not only dispense with one valve-neck, thus saving the

cost thereof, but that my bulb is more durable, because it is not cut or punctured at one of its ends, and that I obviate the liability of air-leakage from the bulb just one-half, in that I use one neck instead of two.

Although the neck *C* may be constructed in two parts, as hereinafter indicated, it is obvious that the integral neck shown is far less expensive, and that no such leakage is liable as at the screw-joints of a two-part neck.

The valve-neck *C* of the intermittent atomizer, Fig. 4, differs from that already described only in that the eduction-passage *c* has no valve, but is extended through the usual metal air-pipe, *a'*, to the jet-aperture of the atomizer. In this neck the induction-aperture *b* is provided with the valve *b'*, as before described.

As compared with one class of prior intermittent atomizers wherein a valve is employed, I obviate the cost and use of a second neck, the liability of leakage incident thereto, and have increased durability in the bulb, as in the continuous atomizer before described.

I am, of course, aware that with the prior atomizers having a single air-passage for induction and eduction, and terminating at the jet-aperture, the bulb having but one neck would be as durable as mine, except that in such atomizers volatile vapors are liable to be taken into the bulb and be more or less destructive to the rubber of which the bulbs are composed. I also know that the bulbs of the intermittent atomizers having a valve in the standard opposite the jet-aperture would be as durable as mine, so far as relates to having one opening in the bulb; but it is obvious that an air-jet aperture cannot be relied upon for induction in a continuously-operating atomizer; and, also, that the prior standard having on one side thereof a projecting jet-pipe and on the opposite side a valve cannot be used for continuous atomizing, for the reason that the air-jet aperture and the bulb directly communicate with the valve-chamber, whereas my novel neck is capable of use for either intermittent or continuous atomizers, because its two air-passages independently communicate with the interior of the bulb, and either passage can be provided with a valve.

Another characteristic feature of my invention is that a neck having air induction and eduction passages is by me interposed between the bulb and the air-pipe, whether the latter be the flexible air-tube for continuous atomizers or the metal air-pipe for intermittent atomizing. This last-named combination with the atomizer-standard, the bulb, and the air pipe or tube shown, with a neck interposed between the air-pipe and bulb, and containing a passage for the induction of air, and a passage by which the air is forced into the air-pipe on its way to the air-jet aperture, at which it operates upon the tip of the liquid-pipe, and where the atomizing is effected, is broadly new, and I therefore do not limit myself in this combination to the precise construction of neck or the rela-

tive arrangement of the air-passages therein which I have shown and described, for I am well aware that many variations can therein be made without materially affecting the results which accrue, nor substantially departing from my invention.

While for economy and for attaining the best results generally, the necks should be constructed in one piece, it is nevertheless desirable to employ a neck containing independent induction and eduction passages, even if the neck be constructed in two parts, as illustrated in Fig. 5, wherein is a screw-joint, at *d*, for affording a valve-chamber and seat, as heretofore provided for in each of the two valve-necks heretofore employed in continuous atomizers, or as in one of the necks of such intermittent atomizers as embody a valve.

Having thus described my invention, I claim as new and desire to secure by Letters Patent—

1. The atomizer-neck constructed to receive a bulb at one end thereof, and provided with independent induction and eduction air-passages, which terminate at the bulb-receiving end of the neck, substantially as described.

2. The combination, with an atomizer-stand-

ard constructed to occupy the neck of a bottle, of an air-pipe connected to and projecting from said standard, a bulb, and a neck interposed between said air-pipe and bulb, and provided with an air-induction passage and a valve, substantially as described.

3. The combination, in an atomizer, of the bulb and a neck connected therewith, which is provided with two valves, respectively for controlling the induction and eduction of air, substantially as described.

4. The combination of a flexible bulb, a flexible tube, and a neck interposed between them, provided with independent induction and eduction air-passages, and valves for each, respectively located within said bulb and said tube, substantially as described.

5. An atomizer-neck constructed in one piece and provided with independent induction and eduction air-passages, and adapted at its ends to respectively connect with a bulb and a tube, substantially as described.

WILLIAM A. TURNER.
